PROCESS FOR MAKING RUGS AND MATERIAL THEREFOR

Charles F. Hutter, Austin, Tex.

Application May 12, 1941, Serial No. 393,139

4 Claims. (Cl. 2—278)

This invention relates to the making of rugs, mats and like articles having a tufted or fluffy surface, and is particularly concerned with the making of so-called "fluff" rugs wherein relatively short strands of yarn or other fabric fibers having free ends are sewed onto a base in rows with the free ends projecting upwardly and defining the nap of the rug.

Rugs of this type have been made for generations, both as a domestic pastime and on a commercial scale. The present invention has to do primarily with making of rugs by individuals, generally but not necessarily in homes, and an object of the same is to provide a method and means whereby material for making rugs of this type may be prepared in package form, or as an article of manufacture, and sold in the open market and thereafter applied to a suitable base easily and accurately.

Another object is to provide a process of preparing material for "fluff" rugs by means of which rug making will be rendered a pleasant as well as a profitable diversion to people in homes or other places where they may be able to utilize spare time and which will ensure accurate rug making irrespective of experience in this field.

In practicing my improved method, strands of fabric fibers such as yarn, string, twine or other material capable of providing a suitable nap are wound on a form or core, preferably cylindrical in shape, and holding strips of adhesive such as paper, Cellophane or the like are then applied to the coils at right angles to the latter and in spaced relation to one another. The material may then be removed from the cylinder in the form of a layer or square by cutting along one of the spaces between a pair of adhesive strips.

In applying the material to a base, it is separated into bands by cutting along alternate spaces between the strips of adhesive, and each band so separated is attached to the base as by stitching, either with a sewing machine or manually, the line of stitching being made along the space between each adjacent pair of adhesive strips. As one band of fluff or nap is laid or attached, the adhesive strips are removed therefrom and a succeeding band of fluff or nap laid in a like manner, the spacing of the bands with respect to one another as well as the closeness of the coils on the cylinder determining the thickness of the tufts or nap of the rug.

A single core may be used as a form and the material cut from the core and packed in layers and sold in the open market in this manner, or the material may be sold on the cores.

The accompanying drawing is illustrative of the process and therein:

Fig. 1 shows a cylinder of prepared rug material;

Fig. 2 is an end view of Fig. 1;

Fig. 3 shows a layer or square of material removed from the cylinder ready for cutting in bands;

Fig. 4 shows one of the bands being applied to a base;

Fig. 5 is an edge elevation showing one band attached and a succeeding adjacent band in the process of being laid;

Fig. 6 is a perspective view of a portion of a completed rug.

The numeral 10 designates a cylindrical form or core which may be made of cardboard, having wound thereon a continuous strand of material such as yarn, string, thread or the like indicated at 11. The windings of the strand 11 may be compact or spaced apart, depending upon the desired density or thickness of the tuft or nap. Strips of adhesive 12 are then applied lengthwise of the cylinder with the strips substantially uniformly spaced from one another, defining alternate longitudinal severing and stitching spaces 13 and 13'. These retaining strips may consist of gummed paper, Cellophane or the like. The material may then be removed from the form or core 10 by cutting along any one of the spaces 13 or 13' and laid out in the form of a square, note Fig. 3. These squares may be packed or packaged and sold in the open market.

In applying the material to a base 14, it is separated in bands by cutting along the space 13, for example, to produce the band of predetermined short length strands shown at the top of Fig. 3, and this band is attached to the base by stitching along the space 13'; note Fig. 4. This may be done with an ordinary sewing machine, and in fact the method is conducive to the use of a sewing machine. After one band of nap or fluff severed strands has been attached to the base, the adhesive strips which are of a width substantially equal to one half of the length of the severed strands are removed and a succeeding nap band is placed parallel to the attached band and sewn to the base in a like manner as indicated in Fig. 5. The spacing of the bands in conjunction with the compactness of wind of the coils determines the density of the fluff or nap.

If desired, each alternate longitudinal space may be slightly greater than the intermediate space, with the narrower space defining the line of sewing and the slightly broader space defining

the line of cut, or vice versa. The width of the adhesive material may of course be varied as desired, its width primarily determining the depth of the fluff or nap. These strips also serve as a guide for laying the bands of nap exactly parallel to one another. The strips of adhesive may be attached over or under the coils or it may be interlaced through the latter.

The material can be readily prepared and packaged in standard lengths and given size numbers and sold in the open market. This method of preparing material stimulates interest and ensures an attractive job by inexperienced persons.

It will be understood that the material may be wound on any type of form or core desired, either cylindrical, square, oblong or the like, and that the strands may be either continuous or in unconnected lengths, although they are preferably continuous, and that these and other modifications may be made without departing from the spirit or scope of the invention as defined by the appended claims.

What is claimed is:

1. The method of making rugs or the like that includes the following steps; forming a layer of longitudinally disposed fibers, attaching to said layer a series of spaced apart removable holding strips transversely arranged with respect to said fibers, severing said layer transversely with respect to said fibers into a plurality of bands of fibers held in position by a pair of said spaced apart holding strips, securing a plurality of said bands in side by side relationship to a base along the space between said pairs of holding strips, and subsequently removing said holding strips from said fibers.

2. A method of making rugs or the like that includes the following steps; winding a layer of longitudinally disposed fibers on a form, adhesive-ly attaching to one surface of said layer a series of spaced apart holding strips transversely arranged with respect to said fibers, severing said

layer transversely with respect to said fibers to form thereby a plurality of bands of said fibers held in position by a pair of said spaced apart holding strips, stitching a plurality of said bands in side by side relationship to a rug base along the space between said pairs of holding strips and subsequently peeling said holding strips from said fibers.

3. As an article of manufacture, rug material comprising parallel closely disposed strands or fibers such as yarn, string, or other material capable of providing a suitable nap when severed in bands of predetermined short length strands, and a series of strand-retaining strips of adhesive material secured transversely over said strands, said adhesive strips being substantially uniformly spaced from one another along the length of the strands, said retaining strips being of a width substantially equal to one half the length of the severed strands, each alternate space defining a line of severance for cutting the material into said bands of predetermined length strands, and the other alternate spaces serving as guides for stitching the severed strands to a suitable base, said adhesive strips being removably applied so that after the stitching has been completed, they may be readily removed to release the severed strands on opposite sides of each line of stitching and provide a nap of a length substantially equal to the width of said strand-retaining strips.

4. As an article of manufacture, rug material comprising a band formed of a layer of parallel closely disposed severed strands of uniform length, and a pair of closely spaced strand retaining strips of readily removable adhesive material secured transversely of the strands from end to end of the band, said strips each being of a width substantially equal to one half the length of the severed strands, and the space between the strips serving as a guide for stitching the severed strands directly to a suitable base.

CHARLES F. HUTTER.
